WINTHROP K. HOWE, OF ROCHESTER, NEW YORK, ASSIGNEE TO GENERAL RAILWAY SIGNAL COMPANY, OF GATES, NEW YORK, A CORPORATION OF NEW YORK.

TRAIN CONTROL.

Application filed September 1, 1922, Serial No. 585,676.

This invention relates to automatic train control systems, and more particularly to systems wherein predetermined speed limits are enforced at successive points in a block 5 to bring the train to a stop before entering a danger zone.

In train control systems of the type just referred to the amount of trackway equipment depends largely upon the number of 10 control points. Since in this type of system speed limits are only enforced at points along the track, as distinguished from a continued enforcement of restricted speeds, it is necessary to restrict the speed at a 15 control point sufficiently so that the train can be stopped when continuing this restrictive speed, or accelerates to the next following control point in advance thereof, and so that if the brakes are applied at 20 this following control point the train will be stopped before entering the danger zone. Under ordinary working conditions, it is often found satisfactory, and likewise economical, to impose a speed restriction at a 25 comparatively few control points only for each braking distance, thereby making the speed limit which must be enforced at each control point to insure safety considerably less than the speed from which the train 30 might be brought to a stop if the brakes were applied at such point. In other words, if only a few control points are employed in each block in this type of system, the speed limits enforced at such control points 35 will in the interests of safety be less than the speeds the engineer might run in making a stop at the signal. Consequently, if the engineer is to regulate his speed so as not to be automatically controlled, he must 40 pass the successive control points at speeds such as would stop his train short of the signal, that is the engineer must aim to stop or shoot, so to speak, at an imaginary signal location some distance in the rear of the signal. This is not only confusing to the engineer, but is also contrary to the usual 45 train operating practice.

One of the principal objects and purposes of the present invention is to give the engineer the usual and proper information in

regard to the point at which he must attempt to stop the train without impairing the safety thereof, so that if the engineer fails to do so and the train is stopped at a later point by the automatic equipment, it 55 will still be brought to a stop before reaching the danger zone. A further object of the present invention is to increase the capacity of railroads employing train control devices which enforce predetermined speed 60 limits at successive control points through blocks, by overlapping the control from certain sections of trackway, thereby permitting closer spacing of moving trains.

Although the principles underlying the 65 present invention may be applied to any type of speed control system, this invention has for convenience been shown in connection with one type of system only, namely, a speed control system employing the time-distance interval principle, that is, the imposition of a restrictive speed by allowing the train to travel a predetermined distance in a predetermined period of time as illustrated 70 in the accompanying drawings, in which:— 75

Figure 1 shows several blocks of the trackway equipment of a train control system embodying the present invention and illustrates speed distance curves, one of which corresponds to the speeds at different points 80 in the block at which if the brakes are applied at such points the train will be brought to a stop before reaching the entrance to the danger zone, and the other corresponds to the maximum speeds at which 85 the engineer may operate a train at the several control points without an automatic brake application terminating at the signal location;

Fig. 2 illustrates in a diagrammatic and simplified manner a portion of the trackway equipment illustrated in Fig. 1, and car-carried equipment adapted to cooperate therewith, the several devices being shown with a view of making it easy to understand 90 the nature of the invention, rather than the particular construction preferably employed 95 in practice; and

Fig. 3 is an enlarged sectional view of the friction slip clutch shown in Fig. 2. 100

In describing the invention in detail, attention is particularly directed to Fig. 1, which shows the trackway devices of a train control system for enforcing successive decreasing predetermined speed limits when cooperating with suitable train-carried devices such as illustrated in Fig. 2. These track devices comprise rails 1 divided into track sections or blocks by insulated joints 2, one block I and the adjacent ends of two other blocks H and J being shown, each of these blocks extending from one insulated joint 2 to the next insulated joint 2 as illustrated. Since the several blocks are the same, like parts thereof will be given the same reference characters with distinctive exponents. These blocks are again divided by insulated joints 3 to form a main section provided with the usual track battery 4 and track relay 5, and an auxiliary or overlap section provided with a similar track battery 6 and a track relay 7.

Near the entrance to each block is provided a home relay 8, which is normally energized by the two track relays 5 and 7 of said block and by the track relay 7 of the block next in advance. The circuit for energizing this home relay 8 for the block I may be traced as follows:—Beginning at the terminal B of a suitable source of energy such as a battery, wire 9¹, front contact 10¹ of track relay 7¹, wire 11, front contact 12 of track relay 5, wire 13, front contact 14 of track relay 7, wire 15, winding of home relay 8, wire 16 back to the common return wire C leading to the other terminal of said source of energy.

Each of the blocks is provided with suitable spaced devices which under caution traffic conditions will communicate control influences to the passing train, the train being provided with suitable cooperating devices and control equipment which will apply the brakes of the train if the train passes two such spaced devices in less than a predetermined time. In the particular embodiment illustrated, these trackway devices comprise pairs of track elements or inductors T and t, comprising a U-shaped core 17 terminating in enlarged pole pieces 18 (see Fig. 2), the second track element t of each pair being provided with a coil 20 which, under normal clear traffic conditions, is closed in a circuit of low resistance. These track elements are controlled by the home relay 8 of the next block in advance, and since the track elements and their control circuits at the successive control points are the same except for the spacing and location of these elements, they will be given like reference characters with distinctive alphabetical exponents. The control circuit for the track elements t of the block I may be traced as follows:—Beginning at a suitable common return or ground wire C, front

contact 23¹ of the home relay 8¹, wire 24, coil 20 of track element t, wire 25 back to the common return wire C, the circuits for the other track elements being the same have their parts designated by like reference characters with distinctive exponents.

In order to limit the speed of a train in entering a block under clear as well as caution traffic conditions, an extra element T^x has been placed at the entrance of each block spaced a suitable distance from the first track element T of the first pair so as to enforce the desired entrance speed, the operation of which will be more specifically described in the operation of the present invention. If blocks are encountered in practice which are considerably shorter than the braking distance of a train at high speed or under adverse circumstances, several elements T^x may be placed in advance of the first pair of track elements T and t and extending into the block in the rear.

Although any type of wayside signals may be employed in connection with the track circuits, and other trackway equipment of the present train control system, light signals of the well-known distinctive color unit type have been illustrated by the green, yellow and red lights G, Y and R respectively. Near the entrance of each block is located a repeater or distant relay D, which is controlled by the home relay 8 of the next block in advance. Back and front contacts operated by this distant relay D in combination with similar contacts operated by the home relay 8 control the light signals in the usual manner, as is readily apparent from the drawings, the green lamp G being energized when both of these relays are energized to indicate clear, the yellow lamp being energized when the home relay 8 is energized and the distant relay D is deenergized, and the red lamp R being energized when the home relay 8 is deenergized.

One type of car-carried apparatus adapted to cooperate with the trackway apparatus illustrated in Fig. 1 has been illustrated in Fig. 2, and comprises suitable devices which will first be separately described. One of these devices comprises an influence receiving car element L mounted on the car so as to have a definite and cooperating relation with the track elements T and t heretofore described, this being preferably accomplished by mounting it directly on the truck frame and protecting it from excessive jars and vibration, and from the weather, in any suitable manner. This car element L comprises a U-shaped core 30 terminating in enlarged pole pieces 31, a primary coil P on one of the legs of the U-shaped core, and a secondary coil S on the other leg.

A control relay C and a repeater relay RR are provided which are particularly de-

signed to properly function for the purpose for which they are intended. Although these relays have been illustrated as identical, this illustration is merely conventional and in practice the control relay is constructed with much smaller moving parts and controls smaller contacts than does the repeater relay RR, and will therefore be more sensitive and function on a smaller change of energy. Both of these relays C and RR have their moving parts well balanced so that they will not be materially affected by jars and vibration, and are preferably mounted in a comparatively heavy spring supported relay casing, which may be provided with a glass panel and locked or sealed in any suitable manner.

The car-carried devices also include a train control device K, which has been illustrated as an electro-pneumatic valve. This train control device K may control the train in any suitable manner as, for instance, by venting the brake pipe when its winding 32 is deenergized. This device K is of the normally energized type, and is normally energized through a stick circuit completed through the front contact 33 controlled by the armature of its electro-magnet. Consequently, a momentary deenergization of the train control device K by deenergization of its winding 32 will permanently deenergize it, because its energizing circuit will have been interrupted at its front contact 33.

The car apparatus further includes a time-control device generally designated by TC. This time-control device TC is provided to normally close an auxiliary circuit, to open this circuit for a very short period of time after this device has been initiated, to maintain this circuit open for a predetermined time, and then again close said auxiliary circuit. This time-control device TC comprises a motor M, having an armature provided with a commutator 34, brushes 35, a shunt field winding 36, and a suitable source of energy illustrated by a battery 37 connected across the brushes and shunt winding so as to permanently operate the motor at a substantially constant speed. This motor is preferably one that will maintain a constant speed irrespective of a slight variation in the voltage of the battery 37, and regardless of a slight change in load applied thereto. This operating characteristic may be obtained to a large extent by proper design, and if desired, a suitable speed control regulator may be incorporated therewith to give this motor a constant speed characteristic.

The motor M through the shaft 38, friction slip clutch 39, shaft 40 and worm 41 drive the worm wheel 42, provided this worm wheel 42 is free to rotate. The construction of the friction clutch 39 is such that it will slip and allow rotation of the motor M without rotation of the worm wheel 42 with-

out undue heating of this clutch, thus allowing a predetermined torque to be applied to the shaft 40, and comprises two clutch members 39 and 29 respectively which are urged into frictional engagement by a spring 28. The worm wheel 42 has fastened thereto but insulated therefrom a contact arm 43, which is connected to one terminal B of a suitable source of energy, such as a battery. As the worm wheel 42 is rotated in the direction of the arrow by the motor M through the intervening slip clutch 39, the contact arm 43 is stopped by coming in contact with the dog 44 of the time-starting magnet CS. This dog 44 is connected to the armature 45 pivoted at 46. When the time-starting magnet CS is deenergized, the spring 47 moves the dog 44 and allows the contact arm 43 to be freely rotated. Although a specific form of time-control device has been shown and described, obviously any other type of device which will carry out the desired functions heretofore mentioned will suffice, the specific device illustrated merely being shown to represent conventionally a time-control device having these operating characteristics.

Operation.—Assume that the car-carried apparatus illustrated in Fig. 2 is in its normal condition, that is, is moving between control points in a block when the next block in advance and the overlap section of the following block are clear. Under these conditions, the control relay C is energized through a circuit which may be traced as follows:—Beginning at the terminal B of a battery which has its other terminal connected to a common return wire N, wire 50, front contact 51 of the control relay C, wires 52 and 53, winding of the control relay C, wire 54, secondary coil S, wire 55 back to the common return wire N.

With the control relay C in its energized position, a circuit will be completed for energizing the secondary or repeater relay RR, through a circuit which may be traced as follows:—Beginning at the terminal B of a battery, wire 50, front contact 56 of the control relay C, wire 57, winding of the repeater relay RR, wire 58 back to the common return wire N.

The energization of the repeater relay RR closes its front contact completing the energizing circuit for the time-starting magnet CS, which may be traced as follows:—Beginning at the terminal B of a battery, wire 60, front contact 61, movable contact 62 and front contact 63 of the repeater relay RR, wire 64, winding of the time-starting magnet CS, wire 65 back to the common return wire N.

Another circuit, namely, the main energizing circuit for the train control device K, is also energized when the repeater relay RR is in its energized position, and may be

traced as follows:—Beginning at the terminal B of a battery, wire 60, front contact 61 and movable contact 62 of the repeater relay RR, wires 66 and 67, front contact 33 of the time-control device K, wires 68 and 69, winding 32 of the train control device K, wire 70, primary coil P of the car element L, wire 71 back to the common return wire N.

10 An auxiliary circuit for energizing the train control device K may be traced as follows:—Beginning at the terminal B of a battery, wire 72, contact arm 43, stationary contact 73, wire 74, release switch 75, wire 67, front contact 33 of the train control device K, wires 68 and 69, winding 32 of the train control device K, wire 70, primary coil P of the car element L, wire 71 back to the common return wire N.

20 The energization of the primary coil P produces a magneto-motive-force in the core of the car element L which greatly predominates the magneto-motive-force produced by the secondary coil S connected in the energizing circuit of the control relay C. This is due to the fact that the current flowing through the control relay C is very small, that is, is just sufficient to maintain it in its energized position. The magneto-motive-force produced by the primary and secondary coils, although being in the same direction, produce very little flux linking both of these coils, this being due to the large air gap between the pole pieces 31.

30 With the car apparatus in its normal condition as just described, let us assume that the train is entering the block I (see Fig. 1) under clear traffic conditions. As the car element L passes over the track element T^x, the reluctance through the magnetic circuit including the core 30 of the car element L is momentarily reduced. This change in reluctance causes a sudden increase of flux and then a decrease to its normal condition, this change of flux being partly due to diversion of flux from leakage paths, and partly due to an increase in the total flux through the primary coil P. This sudden increase and decrease of flux through the secondary coil S induces a voltage therein similar to that of a single cycle of alternating current E. M. F. The secondary winding S is so connected with respect to the battery included in this circuit that the first wave of the unicycle 55 of E. M. F. opposes that of the battery, thereby reducing the energizing current of the control relay C to an extent to drop its armature by the action of the spring 76. Since the control relay C is connected in a stick circuit, it will be permanently deenergized until picked up by some other means.

60 The control relay C having been deenergized, interrupts the energizing circuit for the repeater relay RR, thus causing its armature to drop by the action of the spring 77,

thereby interrupting one of the circuits for energizing the train control device K heretofore traced. The other of said circuits, namely, the auxiliary circuit, being completed through the contact arm 43 is, however, intact and therefore the train control device K will not be deenergized. The deenergization of the repeater relay RR closes a pick-up circuit for the control relay C, which may be traced as follows:—Starting 75 at the terminal B of a battery, wire 72, contact arm 43, stationary contact 73, wire 74, release switch 75, wire 66, movable contact 62 of the repeater relay RR, back contact 78, wires 79 and 53, winding of the control relay C, wire 54, secondary coil S, wire 55 back to the common return wire N. This causes the control relay C to be again energized, causing it to complete the previous energizing circuit including its own front contact as heretofore traced, thereby again energizing repeater relay RR.

This momentary deenergization of the repeater relay RR, as just explained, interrupts the normally energized circuit of the time-starting magnet CS, thereby causing the dog 44 to release the contact arm 43, thus permitting the arm 43 to start on its cycle of rotation. The several parts of the time-control device are so designed and constructed that the auxiliary energizing circuit for the train control device K, which is carried through the contact arm 43, will not be interrupted until the repeater relay RR has again been energized to complete the other or main circuit for the train control device K, and consequently the train control device K will not be affected when passing over a single element.

Let us assume that the train is moving at 105 a speed less than the permissive entrance speed of a block, that is, the speed is low enough to allow the contact arm 43 to complete its travel of one revolution, and again to be stopped by the dog 44 during the time 110 the train travels from the track element T^x to the track element T^a. If now the track element T^a is passed over, the same cycle of operation will take place as just explained, without in any way affecting the train-control device K.

Let us assume now that the train is exceeding the permissive entrance speed, and reaches the track element T^a before sufficient time has been allowed for the contact arm 43 to again reach its stationary contact 73. The control relay C will again be deenergized in the same manner as heretofore described, thereby deenergizing the repeater relay RR. Bearing in mind that the contact arm 43 is on its cycle of rotation and has not yet reached its stationary contact 73, and therefore that the auxiliary circuit is now interrupted, the deenergization of the repeater relay RR will momentarily deener-

gize the train control device K. Since the train control device K is connected in a stick circuit including the front contact 33 thereof, a momentary deenergization of the train control device K will permanently deenergize it, thereby applying the brakes. The pick-up circuit for the control relay C will not be closed due to the making of the back contact 78, because there is no source of energy connected to the movable contact 62, this energy having been received from the contact arm 43 under previous conditions. When the contact arm 43 reaches the stationary contact 73, the pick-up circuit for the control relay C heretofore traced will be completed, thus causing it to pick up and again energize the repeater relay RR. The energization of the repeater relay RR closes the circuit for the time-starting magnet CS to again move the armature 45 against the stop 80, thereby stopping the contact arm 43 when it has completed its cycle of rotation. The train control device K having been deenergized, as just explained, causes the train to come to a stop automatically. In order to again proceed, it is necessary for the engineer to operate the release switch 75. This release switch may be contained in a locked box, the key of which is held by some other person, such as the conductor, so that a certain amount of publicity is connected with such automatic brake application; or it may be accessible only from the ground so that it is necessary for the engineer to wait at least until the train has been brought to a stop before this release switch 75 can be operated. The circuit for energizing the winding 32 of the train control device K, by operating the release switch 75 after an automatic brake application has occurred, as just explained, may be traced as follows: —Beginning at the terminal B of a battery, wire 60, front contact 61, movable contact 62 of the repeater relay RR, wire 66, release switch 75, wires 81 and 69, winding 32 of the train control device K, wire 70, primary coil P, wire 71 back to the common return wire N. The train control device K having now again been energized through its energizing circuit heretofore traced, including its stick-up contact 33, allows the train to proceed under the control of the engineer. It should be observed that this train control device is of such a character that when two successive control influences are received in less than a predetermined time (the time required for the contact arm 43 to make one revolution), the train control device K will be actuated. Therefore, it is possible to limit the speed of the train to any desired value by spacing the track elements a distance which the train may travel at the speed in question during the time set off by the time control device TC. The operation of the automatic brake control apparatus is,

therefore, dependent upon the average speed of the train between two successive track elements. The time-interval allowed by the time control device TC is preferably comparatively short, so that the track elements 70 will be spaced relatively close together, thus making the average speed approximate the actual speed when going over the second track element of such a pair.

Having now considered the entrance of a train into a clear block, both when the speed is less and more than the permissive entrance speed, let us consider the movement of a train into the block I under clear traffic conditions at a speed lower than the permissive entrance speed into the block I but higher than the permissive speed allowed under caution traffic conditions by the track elements T^a and t^a . As the train passes by the track element T^a , the time-control device 75 will be initiated upon its cycle of operation, thereby opening the auxiliary circuit for the train control device K for a predetermined interval of time, as heretofore explained. As the car element L now passes over the next track element t^a , the train control device K will not be deenergized even though the auxiliary circuit thereof is open at this time. This is accounted for by reason that the passage of the car element L over the track element t^a having its coil 20^a closed in a circuit of low resistance, causes very little change of flux through the secondary coil S of the car element L. One theory of operation which accounts for such slight 95 change of flux in the car element is that a slight change of flux through the track element t^a induces a comparatively large current in the coil 20^a, which at this time is closed in a circuit of low resistance, this current being in a direction to oppose the flux producing it and therefore prevents further passage of flux through the track element. This slight change of flux through the track element t^a likewise causes only a slight 100 change of flux through the secondary coil S of the car element L, which is insufficient to induce enough voltage to deenergize the control relay C, and therefore the repeater relay RR will be maintained energized and 105 the brakes will not be applied even though the train exceeds the permissive speed allowed by these elements T^a and t^a .

With the block I under caution traffic conditions, the home relay 8¹ of the block J 120 will be deenergized because one of the sections of the next block in advance or the overlap section of the following block are occupied by a train, or are in danger for some other reason, which causes the track relay of the particular section occupied to drop its armature, thereby opening the energizing circuit for this home relay 8¹ heretofore traced. With this home relay 8¹ deenergized, each of the track elements t will 125

be open-circuited, and therefore will affect the car-carried apparatus of the passing train in the same manner as the track elements T^x and T^a , as heretofore explained.

5 With the train moving in a caution block at a speed higher than that enforced by the track elements T^a and t^a , the passage of the car element L over the track element T^a will start the time-control device upon its usual 10 cycle of operation, as heretofore explained. As the car element L now passes over the next succeeding track element t^a , insufficient time having been allowed for the contact arm 43 to reach the stationary contact 73, 15 the passage of the car element over the track element t^a will deenergize the control relay C and repeater relay RR respectively, thereby deenergizing the train control device K because the auxiliary circuit for this 20 device is still open at the contacts 43-73 of the time-control device TC. The brakes will, therefore, be applied to bring the train to a stop as heretofore explained, the engineer being required to operate the release 25 switch 75 in order to again proceed. Under caution traffic conditions, a predetermined speed will be enforced at each of the succeeding pairs of track elements, such as the track elements T^c and t^c in the same manner 30 as just explained, in connection with the passage of a train over the track elements T^a and t^a , the only difference between these several pairs of track elements residing in their spacing, which decreases as the exit 35 end of the block is approached, thereby enforcing gradually decreasing permissive speeds upon a passing train.

Various methods may be used to determine the spacing between pairs of track elements, and the control points at which these pairs are to be located as well as the length 40 of the overlap track circuit, as long as this overlap track section is sufficiently large to prevent the train from running therethrough 45 if a brake application is made at any of the control points at the highest speed that the train is apt to have when passing such point. For instance, if the engineer passes a control point at the entrance of the block 50 at a speed lower than the permissive speed at this point, he would not have a higher speed than this at the following control point unless the train accelerated; and if such acceleration is to be taken into consideration, there is a limited speed above 55 which the train can not get.

In Figure 1 of the drawings has been 60 illustrated one method of determining the location of the various track elements and the length of the overlap track section. In this particular layout, it has been assumed that the engineer will not accelerate his train when running in a caution block. If such acceleration had been taken into consideration, the various control points would pref-

erably be closer together, and an additional number of pairs of track elements added. The length of the overlap section of track-way can be determined by a cut-and-try method which is obvious after having a clear 70 understanding of the method presently to be described. The length of this overlap section having been determined, which depends upon the number of control points which are to be used, same may be laid off graphically 75 to determine the point at which the train would come to a stop by an automatic brake application when it is traveling at the highest speed it can assume at a preceding control point substantially as shown by the distance OL laid off in Fig. 1 of the drawings. From the righthand end of this overlap block, a curve, conveniently called the brake application curve, may be drawn back as 80 illustrated by the dot and dash curve 91, which represents points along the track at which if a brake application is initiated, the train will stop at or before the end of the overlap section. From the entrance to this overlap section, that is, from the point of location of the signal, another curve may be drawn, as illustrated by the solid line 92, which may for convenience be called a speed-distance brake performance curve and represents the speeds at various points along the 85 track at which the train is running when, with its brakes applied, it stops at the signal. A low permissive speed having been determined at which the engineer may pass the signal will then be laid off, as shown by the dotted line 93, representing seven miles 90 per hour in the present arrangement.

The last pair of track elements T^d and t^d will be located at a point along the track corresponding to the point where the line 93 105 crosses the curve 92, in a manner so that a vertical line through this point falls substantially midway between these track elements. These track elements T^d and t^d will be spaced to enforce this low permissive speed of seven miles per hour. A dotted line 110 94 may then be projected up vertically from the last track element t^d , and where this line 94 crosses the brake application curve 91 represents the permissive speed of the next 115 control point in the rear, as shown by the line 95 representing twenty-one miles per hour. The point midway between the pair of track elements next in the rear namely, the pair T^e and t^e is determined by the point 120 at which the line 95 crosses the curve 92, these track elements being spaced to enforce a speed of twenty-one miles per hour. From the track element t^e a vertical line is projected upward as illustrated by the line 125 96, and a horizontal line 97 is drawn from the point where the line 96 crosses the brake application curve 91 and represents the speed to be enforced by the next pair of track elements T^b and t^b , which in the present case 130

is twenty-eight and one-half miles per hour. This same method of locating the points and spacings of the various pairs of track elements may be carried out in any desired number toward the entrance to the block, an additional element T^x being provided to enforce a predetermined entrance speed which a train should not exceed under clear traffic conditions as well as under caution traffic

10 conditions.

The distance from one track element to the other of a pair in each case corresponds to the distance the train may travel in the time set off by the time-control device TC 15 on the car to enforce the particular speed which the train shall not exceed in passing such point. It is, therefore, apparent that trains of different classes may have their time-control devices adjusted to set off different periods of time, thereby causing certain trains to be limited in their speed more than others in a definite ratio for each control point along the track. For instance, let us 20 assume that a freight train has its time element device TC adjusted for two seconds, whereas a passenger train has its time element device adjusted for one second. As these trains pass through a certain block, such as the block I for instance, the freight 25 train will be allowed to run at a speed equal to one-half of the speed at which the passenger train may run at each control point including the permissive entrance speed to the block.

If, as shown, the overlap section for a 30 block is used as part of the braking distance for automatic control for trains in the succeeding block in advance, or in other words, if the automatic brake controlling 35 distances of the blocks overlap, train movement may be said to be facilitated because of the closer train spacing. For example, if the overlap section at the end of block H is used both for safe stopping of trains in 40 block H and also in block I , then the train spacing has been reduced to this extent.

It is thus seen that the present train control system allows the engineer to aim to 45 stop at the signal, and at the same time provides a safe landing place, so to speak, if he fails to control his train to stop at such signal. It should be understood that, although the principles underlying the present 50 invention have been shown applied to a system where speeds are enforced temporarily at points only along the block, it likewise applies to systems where the enforcement of speed is of a continuous character extending throughout a caution block. In a 55 system of this later type, that is, where permissive speeds are enforced at each increment of distance along the block, there is always a difference between the point at 60 which the engineer may be required to stop the train and the point at which suitable

automatic apparatus will bring the train to a stop, if the engineer fails to do so; and the provision and arrangement of the track circuits and signals as illustrated in the present embodiment of this invention may be organized to adapt them for such a continuous speed enforcement system and improve the traffic carrying capacity of railroads employing the invention.

Other deviations from the specific disclosure will be evident to those skilled in the art, and I desire to have it understood that the specific structure shown and described is merely illustrative of the invention, and does not exhaust the various embodiments 75 thereof.

What I claim as new and desire to secure by Letters Patent of the United States, is:—

1. In a train control system of the type which enforces predetermined speed limits at control points in a block by an application of the brakes if the train passes over a predetermined portion of track in less than a predetermined time, of a trackway divided in a small overlap and a large main section 80 having signals at suitable points and provided with trackway devices which permit the engineer to run the train at a speed so that if the brakes are applied the train is brought to a stop at the end 85 of the main section and control devices for controlling said trackway devices which permit a train to pass a previous signal at high speed only if the main section provided with said trackway devices and the overlap section in advance thereof, which extends a distance so that the train is unable 90 to pass therethrough if an automatic brake application occurs, are clear.

2. In a train control system comprising 100 car-carried equipment which will apply the brakes automatically if two successive control influences are received in less than a predetermined time, and a trackway divided into blocks having an overlap track circuit followed by a main track circuit, track devices in each block adapted to cooperate 105 with the car-carried equipment to apply the brakes if the engineer exceeds a speed which will carry the train beyond the exit end of the block if he makes a service brake application, and means for governing said trackway devices controlled jointly by the two track circuits of the block in advance and by the overlap track circuit of the second block 110 in advance, said overlap track circuits extending a distance into the block which the train can not overrun when an automatic 115 brake application has been made.

3. In a train control system of the type 120 in which predetermined speed limits are enforced if the train passes two successive track devices in less than a predetermined time, of means for enforcing predetermined speed limits at the entrance to a block re- 125

5 gardless of traffic conditions including a pair of track devices comprising inert masses of iron, and traffic controlled inert trackway devices located at subsequent points along the track for enforcing gradually decreasing speed limits.

4. An automatic train control system comprising, car-carried devices which will apply the brakes if two successive influences are received in less than a predetermined time, and trackway devices comprising a plurality of pairs of track elements adapted to transmit such influences to the car-carried devices under caution traffic conditions, the elements of successive pairs being spaced to set up decreasing speed limits which elements if these speed limits are just exceeded act to apply the brakes and bring the train to a stop at a danger signal; and a safety zone extending beyond said danger signal a distance so that the train will not pass through said zone if it travels past one pair of track elements at a speed enforced at the previous pair of elements and the brakes are applied when passing the last pair of elements, said safety zone being shorter than braking distance for normal clear speed.

5. In an automatic train control system, the combination with car-carried apparatus of the type in which if two successive control influences are received from the trackway in less than a predetermined period of time the brakes are applied, of trackway means comprising blocks divided into an overlap section and a main section, trackway devices in the main section of said block adapted to cooperate with said car-carried devices permitting the train to travel at a speed so that if the brakes are applied it will be brought to a stop at the end of the main section of the block without incurring an automatic brake application under caution traffic conditions, the various constants being so chosen that if the engineer exceeds such speed limit the train will be brought to a stop automatically before entering the main section of the block next in advance, said overlap section being shorter than said main section.

6. In an automatic train control system, the combination with car-carried devices, of a trackway having signals at suitable points and provided with devices which in cooperation with suitable devices on the train permit the engineer to run the train at a speed so that if the brakes are applied the train will come to a stop at a point at or in the rear of a signal at danger without the initiation of an automatic brake application, and control devices which permit a train to pass through a block at high speed only if the block in advance and a section of the second block in advance thereof, which extends a distance so that the train is unable to pass therethrough if an auto-

matic brake application occurs in said block, are clear, said section being shorter than braking distance for normal clear speed.

7. In a train control system, the combination with car-carried devices, of a trackway divided into blocks having an overlap track circuit followed by a main track circuit, track devices in each block adapted to cooperate with the car-carried devices to apply the brakes if the engineer exceeds a speed which will carry the train beyond the exit end of the block if he makes a service brake application, and means for governing said trackway devices controlled jointly by the two track circuits of the block in advance and the overlap track circuit of the second block in advance, said overlap track circuits extending a distance into the block which the train can not overrun when an automatic brake application has been made.

8. An automatic train control system of the speed control type, comprising a trackway divided into blocks each having an overlap section followed by a main section, means partly on the vehicle and partly along the trackway for automatically applying the brakes of the vehicle if it exceeds successively lower speed limits in traveling through the block under caution traffic conditions with the next block in advance or the overlap section of the second block in advance occupied by another train, said speed limits being above the speed-distance brake performance curve of a train entering at the normal running speed and decelerating under a service brake application to stop at the end of the block, the length of the overlap section being so chosen that if the brakes are automatically applied as a result of exceeding any permissive speed limit the train will be brought to a stop in the overlap section of the next succeeding block, said overlap section being shorter than said main section.

9. An automatic train control system of the speed control type in which the brakes of the train are automatically applied if the speed of the train exceeds predetermined speed limits depending on the position of the train in a block and traffic conditions ahead comprising, a trackway divided into blocks, an overlap section follower by a main section, means partly on the vehicle and partly along the trackway establishing successive lower speed limits in step like fashion under caution traffic conditions when the block in advance or the overlap section of the second block in advance are occupied which permits the engineer to bring his train to a predetermined low speed at the exit end of the caution block in the usual manner without exceeding such speed limits, said means including means whereby if such speed limits are exceeded the brakes of the train are automati-

ically applied and cause the train to be brought to a stop in said overlap section, said overlap section being shorter than said main section.

- 5 10. An automatic train control system of the speed control type in which the brakes of the train are automatically applied if the speed of the train is excessive comprising, a trackway divided into blocks provided with 70
10 the usual closed track circuit having an overlap section followed by a main section, speed restricting means partly on the train and partly along the trackway for setting up successive decreasing permissive speed 75
15 limits falling on a speed-distance brake performance curve which reaches the zero speed value at the end of the block, the spacing between changes in successive speed limits and the length of the overlap section being 80
20 so proportioned that a train passing through a caution block at excessive speed will be brought to a stop by an automatic brake application before it has passed through the 85
23 overlap portion of the next block in advance, said overlap section being shorter than braking distance for a train running at the permissible speed at the entrance to such caution block.

11. An automatic train control system of 90
30 the speed control type in which the brakes of the train are automatically applied if the speed of the train is excessive comprising, a trackway divided into blocks provided with an overlap section followed by a main 95
35 section each having the usual closed track circuit including a track relay, speed restricting means partly on the track and partly on the train for setting up a plurality of decreasing permissive speed limits at successive points of the main section under 100
40 caution traffic conditions when either the block in advance or the overlap section of the second block in advance are occupied consisting of a single speed limit for a certain portion of trackway and for effecting 105
45 an automatic brake application if such permissive speed limits are exceeded, said speed limits, lengths of track portions and the length of the overlap section being so proportioned that the permissive speed at the 110
50 entrance end to each track portion is such that if the brakes are applied the train will come to a stop before reaching the end of the main section of the track, and if the 115
55 brakes are applied at any speed the train may attain in such track portion the train is automatically brought to a stop in the overlap section, said overlap section being as short as possible and which will still assure stoppage of the train within the limits thereof due to an automatic brake application initiated in the preceding block.
12. An automatic train control system of 120
60 the speed control type, comprising a trackway divided into blocks consisting of an 125
65

overlap section followed by a main section each provided with the usual closed track circuit and a track relay, means partly on the vehicle and partly along the trackway for automatically applying the brakes of the vehicle if it exceeds successively lower speed limits in traveling through the block under caution traffic conditions with the next block in advance or the overlap section of the second block in advance occupied by another 70
75 train, said speed limits being above the speed-distance brake performance curve of a train entering at the normal running speed and decelerating under a service brake application to stop at the end of the block, the length of the overlap section being so chosen that if the brakes are automatically applied as a result of exceeding any permissive speed limit the train will be brought to a stop in the overlap section of the next succeeding 80
85 block, said overlap section being shorter than said main section.

13. An automatic train control system of the speed control type in which the brakes of the train are automatically applied if the speed of the train exceeds predetermined speed limits depending on the position of the train in a block and traffic conditions ahead comprising, a trackway divided into blocks 90
95 consisting of an overlap section followed by a main section each having the usual closed track circuit including a normally energized relay, means partly on the vehicle and partly along the trackway establishing successive lower speed limits in step like fashion 100
100 under caution traffic conditions when the block in advance or the overlap section of the second block in advance are occupied which permits the engineer to bring his train to a predetermined low speed at the exit end 105
105 of the caution block in the usual manner without exceeding such speed limits, said means including means whereby if such speed limits are exceeded the brakes of the train are automatically applied and cause 110
110 the train to be brought to a stop in said overlap section, said overlap section being shorter than said main section.

14. An automatic train control system of the speed control type in which the brakes of the train are automatically applied if the speed of the train is excessive comprising, a trackway divided into blocks having an overlap section followed by a main section, each 115
120 provided with the usual closed track circuit including a track relay, speed restricting means partly on the train and partly along the trackway for setting up successive decreasing permissive speed limits falling on a speed-distance brake performance curve 125
125 which reaches the zero speed value at the end of the block when either of the track relays of the sections of the block in advance or the track relay of the overlap section of the second block in advance are deenergized, the 130

spacing between changes in successive speed limits and the length of the overlap section being so proportioned that a train passing through a caution block at excessive speed will be brought to a stop by an automatic brake application before it has passed through the overlap section of the next block

in advance, said overlap section being shorter than braking distance for a train running at the permissible speed at the entrance to ¹⁰ such caution block.

In testimony whereof I hereby affix my signature.

WINTHROP K. HOWE.
